UNITED STATES PATENT OFFICE.

ALPHEUS E. ROE, OF SAN FRANCISCO, CALIFORNIA, ASSIGNOR TO THE
VULCAN IRON WORKS, OF SAME PLACE.

GANG-EDGER.

SPECIFICATION forming part of Letters Patent No. 431,483, dated July 1, 1890.

Application filed November 4, 1889. Serial No. 329,234. (No model.)

To all whom it may concern:

Be it known that I, ALPHEUS E. ROE, a citizen of the United States, residing in the city and county of San Francisco, State of California, have invented an Improvement in Gang-Edgers; and I hereby declare the following to be a full, clear, and exact description of the same.

My invention relates to certain improvements in the construction of gang-edgers or scantling-machines; and it consists in certain details of construction, which will be more fully explained by reference to the accompanying drawings, in which—

15 Figure 1 is an end view showing the gearing and connections for raising and lowering the feed-rolls and the mechanism for changing the saws. Fig. 2 is a plan view of a portion showing the saw-adjusting mechanism. 20 Fig. 3 is an end view showing the means for driving the feed-rolls. Fig. 4 is a side view. A is the frame of the machine.

B is the saw-arbor, journaled in boxes and extending centrally from end to end of the 25 frame, having suitable driving-pulleys upon the end of the arbor.

C are the saws, which are fixed in collars, these collars being fitted to slide upon feathers or keys longitudinally upon the arbor, so 30 as to be moved nearer to or farther from each other, and by this adjustment the width of the material to be cut by the gang of saws is determined. In order to move these saws, each of the collars has a groove or channel 35 cut around it, into which the curved end of the lever-arm E is adapted to fit. This arm is fulcrumed upon a sliding yoke or carriage E', which is adapted to travel upon a guide or way E², parallel with the saw-arbor, and 40 when it is moved one way or the other it acts

through the arm to move the saw with it. The lever-arms E are pivoted to the carriage E', as shown at F, so that if it is desired to remove the saws from the arbor these arms 45 may be turned about their pivots, and thus disengaged from the collars of the saws and turned up out of the way, so that the saws can be slipped off of the arbor. A handle G is fulcrumed to the yoke E', and the inner 50 end of this handle forms a short arm, which

is adapted to engage with teeth or notches H in the figure-bar I, and thus hold the adjusting-arms E and the saws at any desired position.

The figures on the figure-bar I represent 55 certain fractions of lumber measurement, and the teeth or notches H, corresponding with these figures, represent the fractional value of each notch. The weight of the outer end of the handle is sufficient to keep the inner 60 end engaged with its notch; but when the handle is lifted the inner end is disengaged, and the whole device may be pushed to one side or the other, thus moving the saw upon its arbor.

65 The guide or plate E³, by which the carriages or yokes E' are directed, has four grooves e, in each of which one of the slides e' of the yokes is fitted to travel. These grooves or channels are made in the lower 70 face of the plate, so as to prevent sawdust from accumulating in them, and thus preventing the free movement of the slides. These slides are of considerable length, (ten 75 or twelve inches,) so as to move easily, and not bind when the yokes and saws are moved from side to side, and the first four are arranged to follow each other successively in the grooves, after which the fifth and sixth are placed in the first and second grooves 80 again, as they will be so far from the first and second as not to interfere with them, and thus these four guides serve for the adjustment of the whole six saws, as shown in Fig. 2.

J and K are the rolls through which the 85 lumber passes, and by which it is fed to the saws. The upper rolls have each end journaled in boxes j, which move up and down in suitable guides j' upon the end posts of the frame.

90 L L are jointed connecting-rods having the upper ends hinged or pivoted at the upper corners of the frame at l, and the lower ends hinged or pivoted to the upper roll-boxes j, the centers of the rods being hinged together 95 at l'. There are two sets of these rods, one upon each side of the machine, and they are connected together by two parallel rods N, which extend along the sides of the frame of the machine and unite with the connecting- 100

rods at their central meeting-point or knee-joint l' , thus connecting the pair of each side together. The opposite rods L at each end are also connected by transverse rods N' .

5 O is a shaft extending longitudinally of the frame of the machine parallel with the saw-arbor and above it, and P is a second shaft parallel with the shaft O .

10 Q are spur gears or segments mounted upon the shaft P so as to engage with pinions R , which are mounted upon the shaft O .

15 S are crank-links having one end pivoted to the meeting joints or knees of the suspending rods L , while the opposite end of each is connected with the pin q , near the periphery of the spur gear or segment Q , which is mounted upon the shaft P . Upon the end of the shaft O is a flanged pulley T , which receives motion by means of a belt u from a 20 flanged pulley U , mounted upon the end of one of the lower feed-roll shafts.

25 V is a tightener-pulley journaled upon the swinging frame or pendulum W , so that when the tightener-pulley is pressed against the belt which connects the flanged pulleys the shaft O will be caused to rotate in one direction, and by means of the pinions upon this shaft, which engage with the spur gears or segments on the shaft P , these gears or seg-

30 ments will be turned, and through the connecting-links $S S$, which unite them with the connected series of suspending rods L of the upper roll journal-boxes, the movement of the spur-gears will be communicated to these 35 rods and they will be pushed out to one side, thus acting to raise the upper feed-rolls in proportion to the distance that they are pressed to one side. The swinging frame W of the tightener-pulley V is connected with a rock-40 shaft w , which extends along the front of the machine, and said shaft is provided with a continuous handle-bar w' , so that no matter in what position the operator may be standing he can grasp the handle-bar and operate 45 the tightener-pulley.

The feed-rolls are caused to rotate in unison, whatever may be their position, by means of the gears a , b , b , and c . The gear a is fixed upon the end of the lower feed-roll shaft, and 50 a bell-crank or right-angled arm d has one end connected with this shaft, so as to move about it. In the angle and at the opposite end of this arm are fulcrumed gears $b b$, one of which 55 engages with the gear a and the other with the gear c , which is fixed to the upper feed-roll shaft. A single link d' connects the upper end of the right-angled lever-arm d with the upper feed-roll, so that and by this connection it will be seen that the upper feed-60 rolls may be moved up or down by the mechanism previously described without disengaging the gears, the angular levers d and links d' holding them in proper relation with each other, while allowing the feed-rolls to 65 move up or down.

X is a brake-lever, which is connected with and operates a brake x , acting on an inner

flanged face of pulley T on the end of shaft O . The lower end of this lever engages a rack x' , by which it is held in the position 70 to which it may be moved. Now after the feed-rolls have been raised to the required position the brake x may be applied and set fixedly by the lever X engaging its rack x' , and thereby so braking pulley T that it will 75 hold the rolls in the position required.

Y is the drive-pulley on the saw-arbor, and y is a smaller pulley on the arbor. From pulley y extends a belt y' to a pulley y^2 on a 80 shaft Y' above. Upon this same shaft is a pulley y^3 . On one side of this pulley is an idler-pulley y^4 , and on the other side is a tightener-pulley y^5 , carried in the end of a weighted lever y^6 . On the end of the lower feed-roll shaft is a pulley k , and on the end of the shaft 85 of the opposite lower feed-roll is a pulley k' . An endless belt Z passes under pulley y^3 , over tightener-pulley y^5 , down under pulley k across to pulley k' , and up to and over idler-pulley y^4 . By this arrangement the feed-rolls are 90 driven in a direction opposite to the direction of rotation of the saws and without the use of a crossed belt.

Having thus described my invention, what I claim as new, and desire to secure by Letters 95 Patent, is—

1. In a gang-edger, the combination of a series of saws adapted to be moved upon a saw-arbor, the lever-arms having curved ends removably connected with the saw-collars, the 100 sliding yokes to which the lever-arms are pivotally secured, the figure-bar, and the guide-plate E^3 , having a grooved under surface, said yokes being provided with slides e' , engaging the grooves of the guide-plate and having handle portions whose inner ends engage the figure-bar, substantially as herein described.

2. In a gang-edger, the combination of a series of saws adapted to be moved upon a saw-arbor, the lever-arms having curved ends removably connected with the saw-collars, the figure-bar, the sliding yoke pivotally secured to the lever-arms and having gravitating handles whose inner ends engage the figure-bar, the longitudinally-grooved guide-plate, the 115 guide E^2 , and the slides upon the yoke engaging the guides, substantially as described.

3. In a gang-edger, the vertically-movable upper feed-rolls, in combination with the means for moving them vertically, consisting 120 of the jointed rods pivoted at their lower ends to the roll-shaft connections and at their upper ends to the main frame, a rotary shaft in the main frame, and crank-links connecting said shaft with the jointed rods, whereby the 125 latter are bent to raise and lower the rolls, substantially as herein described.

4. In a gang-edger, the vertically-movable upper feed-rolls, in combination with the means for moving them vertically, consisting 130 of the jointed rods pivoted at their lower ends to the roll-shaft connections and at their upper ends to the main frame, a rotary shaft in the main frame, gears on said shaft, crank-links

connected with the gears and with the jointed rods, whereby the latter are bent, and a second rotary shaft in the frame having pinions meshing with the gears of the first shaft, substantially as herein described.

5. In a gang-edger, the vertically-movable upper feed-rolls, in combination with the jointed suspending rod having the lower ends connected with the upper feed-roll boxes and the upper ends pivoted to the upper part of the frame, connecting rods between the jointed rods, whereby the latter operate in unison, a rotary shaft in the main frame having gears, crank-links connecting said gears with the jointed rods, whereby the latter are bent, a second rotary shaft with pinions engaging the gears, and a pulley on the second shaft, whereby it may be rotated, substantially as herein described.
10. In a gang-edger, the vertically-movable upper feed-rolls, in combination with the shaft O, intervening connections by which the rotation of the shaft is directed to vertically move the upper feed-rolls, the pulley T on the end of shaft O and a belt for operating it, the flanged face of said pulley, the brake on said face, the lever for operating the brake, and the rack for holding the lever, whereby the rolls may be held in desired position, substantially as herein described.
15. In a gang-edger, the saw-arbor and the

lower feed-rolls, in combination with the mechanism for driving the feed-rolls in a direction opposite to the direction of rotation of the saw-arbor, consisting of the shaft Y' and pulleys and belt by which said shaft is driven from the saw-arbor, the pulley y³ on the shaft Y', the idler and tightener pulleys on each side, the pulleys k k' on the shafts of the lower feed-rolls, and the endless belt Z, all arranged and adapted to operate substantially as herein described.

20. In a gang-edger, the vertically-movable upper feed-rolls, the belt, pulleys, and intervening power-transmitting mechanism comprising the jointed rods, the rotary shaft on the main frame, and crank-links connecting the shaft with the jointed rods for vertically moving said rolls, in combination with the tightener-pulley for throwing the belt into and out of operation, the swinging frame carrying said pulley, the rock-shaft, on one end of which the frame is carried, and the handle-bar of the shaft extending along the front of the machine, substantially as herein described.

25. In witness whereof I have hereunto set my hand.

ALPHEUS E. ROE.
